LYNDE BRADLEY AND HARRY L. BRADLEY, OF MILWAUKEE, WISCONSIN.

MAGNETIC SHORT-CIRCUITING SWITCH.

1,151,241.

Specification of Letters Patent. Patented Aug. 24, 1915.

Application filed July 18, 1913. Serial No. 779,695.

To all whom it may concern:

Be it known that we, LYNDE BRADLEY and HARRY L. BRADLEY, citizens of the United States, residing at Milwaukee, county of Milwaukee, and State of Wisconsin, have invented new and useful Improvements in Magnetic Short-Circuiting Switches, of which the following is a specification.

10 Our invention relates to improvements in magnetic short circuiting switches.

The object of our invention is to provide means for controlling an automatic motor starter in such a manner that it will automatically protect the motor at all times and under all conditions when used in combination with reversing switches, dynamic braking systems and special control systems, using the so-called operator's switch or master switch.

20 More particularly, the object of our invention is to equip a motor starter of that type having a compressible resistance medium for controlling the current to the motor with means for automatically making the necessary resistance changes required for the protection of the motor more rapidly than it is possible for the operator to move the reversing switch or any lever by which 25 the operator may change the working circuits of the motor.

It will be understood that if a motor starter is connected with a reversible motor, it is virtually essential that when the reversing switch is thrown into the reverse position with the motor running at full speed, the starter must immediately insert resistance in the power circuit to keep the flow of current within safe limits while the 35 motor is being brought to a stop, after which the resistance interposed by the starter must be gradually removed so that the motor may be brought up to the required speed in the reversed direction. Our invention

40 contemplates the provision of automatic means for accomplishing these results in connection with a starter having compressible resistance columns, by removing the pressure from the resistance columns as 45 soon as the required speed of the motor is attained, the current to the motor having been first shunted from said columns. Shunting the columns from the circuit is 50 accomplished in our improved apparatus by 55 means of a magnetic switch which is opened to insert the resistance columns into the cir-

cuit. The time required for the opening of this switch is so short that the resistance will invariably be inserted into the power circuit before any change of motor connections can be completed by the operator, no matter how careless he may be.

60 The drawing is a diagrammatic illustration of our invention associated in controlling relation to an electric motor. The various switch board elements are well known to those familiar with this art and are therefore illustrated conventionally.

65 Compressible resistance columns 1 are preferably composed of graphite disks similar to those described in our former patent for a resistance device, Number 1054902, dated March 4th, 1913. The resistance of these columns decreases under pressure. In our improved construction, pressure is applied to the columns by transmitting motion 70 from the plunger 2 of solenoid 3, through bell crank 4 and an equalizing plate or bar 5, having universal joint connection at 6 with one arm of the bell crank and arranged to bear upon movable electrodes 7 which 75 pass into the tubes and bear respectively against the ends of the graphite columns. These parts are mounted upon a switch board *a*, which is also provided with a magnetic line switch 12, an actuating solenoid 9 therefor, an accelerating relay 13, over-load relay 14, magnetic switch 15, controlled by a solenoid 23, and a compound magnetic circuit relay 19.

80 The several elements above mentioned are organized and electrically connected to operate as follows:—To start the motor A, a push button or switch lever B will be actuated to close contacts 8, whereupon a circuit will be established from + line C, through the points 8, the winding of solenoid 9, resistance 27 and switch bar 28 to — line D. The solenoid 9 is then energized 85 and its core moves upwardly. This core is connected to an elbow of the magnetic line switch 12, causing the tongue 10 of said switch to swing until it strikes contact 11. This bridges the contacts 8 of the push button B through resistance 29, and allows 90 solenoid 9 to remain energized with switch 12 closed after the starting button B has been released and the contacts 8 separated. The operation of switch 12, as above explained, also closes contacts E, whereupon 95 the armature of motor A will receive current from + line C through switch 12, the

coil of series accelerating relay 13, coil of series over-load relay 14 and resistance members or columns 1, (connected in parallel), the electrodes 7 of which are connected to the terminal of the motor armature. The shunt field of the motor is energized by current passing from coil of relay 14 through the field winding F to the — line D.

It will be observed that when the switch 12 is closed, as above described, a tongue 34, carried thereby, strikes contact 32 and connects up the switch 12 electrically with a flexible jumper 30 connected to tongue 16 carried by switch lever 15, but insulated therefrom. In starting position this flexible jumper 30 is electrically connected with the coil of solenoid 3, through contact 17 and a circuit will therefore be established simultaneously with the armature and field 20 circuits, above described, from lever 12 through tongue 34, contact 32, flexible jumper 30, tongue 16, contact 17, the coil of solenoid 3, bar 18, controlled by accelerating relay 13, and thence to the — line D at 25 d. The current in this circuit energizes solenoid 3 and draws plunger 2 downwardly, compressing the resistance columns as above explained. The compression of the columns gradually decreases their resistance with a 30 consequent graduated increase of current flow in the motor armature circuit until such flow reaches a volume sufficient to energize the coil of accelerating relay 13, whereupon bar 18 will be lifted by the magnetic pull 35 upon the relay core. When bar 18 is thus lifted, the circuit through the winding of solenoid 3 is broken, said solenoid is immediately deenergized, and the increase of pressure upon the resistance columns ceases.

40 The motor continues to accelerate and increase its counter electro-motive force, and the plunger 2 also tends to return to its initial position, thus relieving the columns 1 to some extent from pressure and increasing their resistance. These two features 45 quickly reduce the armature current to the point where the accelerating relay 13 is sufficiently deenergized to permit bar 18 to again close said circuit through rheostat solenoid 3 50 to again compress the resistance columns. This alternating action of the accelerating relay 13 and rheostat solenoid 3, will be repeated with sufficient rapidity so that the armature current will remain substantially 55 at the point to which the accelerating relay 13 is set, or adjusted until a stage is reached where the drop in voltage across the resistance units becomes low enough to allow the compound relay 19 to unlock, whereupon this relay operates to close the circuit 60 across points 21. The relay 19 is of the well known compound magnetic circuit type similar to that shown at S—b, S—c, in U. S. patent to Hall, numbered 1053494, dated 65 February 18, 1913, or that shown at L' in

U. S. patent to Eastwood, numbered 1040292, dated October 8, 1912. It is locked open by the excess of magnetic flux when its operating coil is subjected to a voltage greater than that under which it is designed to operate, 70 and it is connected across the circuit of the resistance columns 1. When the voltage drop reaches the required stage and this relay unlocks and connects up points 21, as above stated, a flow of current is permitted 75 from + line C, through contacts 21, coil of magnetic switch 23, to — line D. By energizing magnetic switch 23, its plunger is lifted and switch bar 15 moves to connect up contacts G for direct current delivery 80 from over-load relay 14 through switch bar 15 to the motor, thus shunting or short circuiting the resistance columns 1 from the armature circuit. The coil of relay 19 will also be short circuited by switch bar 15, and 85 relay 19 will therefore open or disconnect points 21 electrically as soon as the winding of magnetic switch 23 is energized. To prevent this electrical separation of contacts 21 from deenergizing the winding of 90 magnetic switch 23, contact 24 is connected through a suitable resistance 33 with the winding of magnetic switch 23, and the arrangement is such that when switch bar 15 swings to close contacts G, tongue 16 will 95 swing downwardly to contact 24, thus permitting current delivery to the winding of magnetic switch 23 from + line C, through switch bar 12, lip 34, contact 32, flexible 100 jumper 30, tongue 16, contact 24, resistance 33, and the winding of switch 23 to — line D. This keeps the magnetic switch 23 energized after relay 19 has opened the original circuit through this switch.

It will be observed that when tongue 16 moves downwardly to contact 24, it separates from contact 17 which originally connected it with the winding of rheostat solenoid 3. The circuit through this winding is therefore broken as soon as switch bar 15 110 closes contacts G. This relieves the pressure upon the resistance columns 1, and such pressure may be wholly removed by spring 31, which is arranged to actuate bell crank 4, whereby equalizer plate 5 is retracted and the core 2 of the rheostat solenoid 3 lifted. This restores resistance units 1 to their condition of maximum resistance, and also prevents consumption of current in the rheostat solenoid (and consequent heating) 115 when the rheostat is not regulating the motor. When it is desired to stop and start the motor in quick succession, it is found that this retrieving of the rheostat solenoid is of great advantage, as these solenoids are 120 of considerable size and slow in their action as compared to the smaller solenoids 9 and 23 of the magnetic line switches. By deenergizing rheostat solenoid 3 and returning 125 the resistance units to their condition of 130

- maximum resistance, the starter is in normal condition of readiness to again regulate the acceleration of the motor the instant magnetic line switches 12 and 15 are opened.
- 5 It will therefore be understood that if the magnetic line switches 12 and 15 should be opened after the motor is running, it will be impossible to re-close them without first permitting the rheostat solenoid to automatically insert resistance into the armature circuit in connection with the above described cycle of current regulating operations.

When it is desired to stop the motor and restore the starting mechanism to its initial 15 position, the button H is pushed to close contacts 26 and thereby short circuit the coil of magnetic switch 9 which, when deenergized, allows switch bar 12 to move to open position, thus shutting off current from the

20 motor and deenergizing magnetic switch 23.

We believe we are the first to provide means for automatically utilizing variations in voltage through a variable resistance current regulating device to shut out such resistance and restore it to normal position ready for automatic operation to protect the motor against injury from intermittent current flow.

A companion application bearing even date herewith, filed July 18, 1913, Serial No. 779,694 shows and describes some of the features illustrated in this application, with claims for an alternative structure designed to accomplish the same general purpose 35 sought to be accomplished in the apparatus herein described. In the companion application, however, the construction is such that the shunting of the resistance columns and rheostat solenoid from the main motor circuit, is dependent upon the attainment of a predetermined pressure upon such columns, whereas in this application it is dependent upon the attainment of predetermined current conditions in the circuit.

40 While we have shown and described our invention as involving the use of a compound magnetic circuit relay in shunt with a compressible resistance column, we do not thereby intend to limit the scope of our 45 claims entirely to this arrangement, since an ordinary electro-magnetic switch or relay may be used in shunt with a motor armature or some other portion of the circuit, to accomplish the same purpose of cutting out, short circuiting or otherwise removing the resistance member when the rise in potential through such portion of the circuit reaches a predetermined degree.

We claim—

60 1. An automatic electrical controlling apparatus, comprising the combination with a main electrical circuit, of a current controlling variable resistance, means for progressively reducing the resistance of said medium, means for utilizing the voltage drop

across said medium to remove said medium from the main circuit after a predetermined drop in the voltage, and means for automatically restoring said medium to maximum resistance when it is so removed from the main circuit.

2. The combination with a main electrical circuit, of a compressible resistance column, electro-magnetic means for compressing the same, means for removing said resistance column from the main circuit, and an electro-magnetic device controlling said removing means and adapted to operate at a predetermined drop in voltage across the resistance column, together with means, controlled by said device, for deenergizing the electro-magnetic compressing means and restoring said column to low pressure condition.

3. The combination with electrically driven apparatus and a main circuit therefore, of a compressible resistance member, a manually controlled electro-magnetic device for closing said main circuit through said compressible resistance member, electro-magnetic means, in shunt with said main circuit, for compressing said resistance member, an electro-magnetic relay operable under a predetermined difference in potential and connected in parallel with said resistance member; an electro-magnetic switch for removing said resistance member from the circuit, and means actuated by the relay for energizing said last mentioned switch.

4. The combination with electrically driven apparatus and a main circuit therefore, of a compressible resistance member, a manually controlled electro-magnetic device for closing said main circuit through said compressible resistance member, electro-magnetic means, in shunt with said main circuit, for compressing said resistance member, an electro-magnetic relay operable under predetermined electrical conditions and connected in shunt with said resistance member, an electro-magnetic switch for removing said resistance member from the circuit, and means actuated by the relay for energizing said last mentioned switch, and means controlled by said last mentioned switch for relieving said resistance member from pressure.

5. The combination with a compressible resistance medium, of an electro-magnetic device operable under predetermined difference in potential across the resistance medium to automatically relieve said medium of pressure.

6. The combination with a main circuit of a compressible resistance medium and an electro-magnetic device, operable under predetermined difference in potential across the resistance medium, to automatically remove said medium from the main circuit.

7. The combination with a main electrical

circuit, of a variable resistance member, a manually controlled switch for establishing the main circuit through said member, an electrically controlled automatic switch for establishing the main circuit independently of said member, and an electro-magnetic relay controlling the last mentioned switch, said relay being adjusted to operate under predetermined variations in potential, together with electro-magnetic means for varying the resistance of said member and permitting restoration of maximum resistance capacity, simultaneously with the closing of the automatic switch, substantially as described.

8. The combination with a main circuit, of a compressible resistance member, means for compressing the same, electro-magnetic means for relieving said member from pressure and removing it from the main circuit, said electro-magnetic means being operative only under predetermined conditions of electro-motive force across said member.

9. In an electric current controller, the combination with a main circuit, of a resist-

ance medium adapted to be included in said circuit, means for compressing said medium and means for automatically removing said medium from said circuit when the voltage drop across said medium is less than 30 a predetermined amount.

10. In an electric current controller, the combination with a main circuit, of a resistance medium adapted to be included in said circuit, means for producing pressure 35 on said medium, electro magnetic means operable under a predetermined voltage drop across said medium and the connections controlled thereby, and adapted to remove said resistance medium from said circuit when 40 the voltage drop across said medium becomes less than a predetermined amount.

In testimony whereof we affix our signatures in the presence of two witnesses.
